UNITED STATES PATENT OFFICE.

PEDRO MIR, OF SAN PEDRO DE MACORIS, DOMINICAN REPUBLIC.

CATCHALL FOR MULTIPLE EFFECT EVAPORATORS AND VACUUM PANS.

Application filed August 26, 1924. Serial No. 734,380.

To all whom it may concern:

Be it known that I, PEDRO MIR, a citizen of the Republic of Cuba, and a resident of San Pedro de Macoris, Dominican Republic, have invented a new and Improved Catchall for Multiple Effect Evaporators and Vacuum Pans, of which the following is a description.

My invention relates to a catch-all to be interposed in the vapor pipe between the vacuum pans and the condenser and the sugar factory for the purpose of trapping or catching the juice or heavy liquor carried by the vapors and returning the same back to the pans.

The general object of my invention is to provide an efficient device for eliminating the liquor and prevent its passing to the condenser.

The nature of my invention and its distinguishing features and advantages will clearly appear as the description proceeds.

Reference is to be had to the accompanying drawings forming a part of this specification, it being understood that the drawings are merely illustrative of one example of the invention.

Figure 1 is a side elevation of a catch-all embodying my invention and showing portions of the vapor pipe;

Figure 2 is an enlarged longitudinal vertical section of the catch-all and pipe portions;

Figure 3 is a section approximately on the line 3—3, Figure 2, the baffle being shown in front elevation;

Figure 4 is a transverse vertical section on the line 4—4, Figure 2.

In forming and installing a catch-all in accordance with the illustrated example, an outer shell is provided which may in practice, as shown, comprise a truncated conical body 10 having at one end an oppositely tapered truncated conical shorter portion 11, the bases of the cones being thus juxtaposed. The adjacent ends of the body 10 and end 11 are formed with outwardly directed annular flanges 12 secured by rivets 13 or other suitable means. The flanges 12 are shown as separate elements of angle form in cross section and riveted as at 14 to the body 10 and end 11, respectively.

An inlet pipe section 15 is secured by annular elements 16 of angle form in cross section riveted as at 17 to the pipe 15 and end 11. The flanges are outwardly directed members, the elements being fastened by

rivets 18. The pipe 15 leads from the vacuum pans (not shown) in practice to conduct the vapors into the catch-all. To the smaller end of the body 10 is connected the outlet pipe 19 leading to the condenser (not shown), the connection being established by annular elements 20, 21 riveted as at 22 to the body 10 and to pipe 19 and riveted to each other as at 23.

Within and spaced from the outer shell is provided a pipe 24 open at one end to the outlet pipe 19 and suitably secured to said pipe as by rivets 25. The opposite end 26 of pipe 24 is closed and disposed oblique to the axis of said pipe so that the top portion of the pipe is the longer. Said pipe 24 has perforations 27 at the top the total joint capacity of which is in practice twice the capacity of the outlet pipe 19 so as to insure a free passage of the vapors through the condenser.

In front of the closed end 26 of pipe 24 at the top portion is a baffle 28 V-shaped in cross section, so that said baffle tapers toward the front and flares rearwardly. The baffle 28 is spaced from the adjacent end of pipe 24 so as to form a passage 29 between said baffle and the closed end 26 of said pipe. Baffle 28 is formed with an outwardly directed flange 30 which is secured between the annular angle elements 12 to be held by the rivets 13.

A discharge pipe 31 leads from the conical end 11 of the outer shell and in practice connects with the vacuum pans to conduct back the heavy liquor trapped in the shell.

In practice the vapors enter the conical end 11 of the outer shell from the inlet pipe 15 and the vapors contact with the baffle 28 and with the closed end 26 of pipe 24. Said vapors thus are caused to pass about the upper end of pipe 24 through the passage 29 to the perforations 28 and thence to the condenser by pipe 19. The vapors entering the catch-all expand and lose velocity in the end 11 causing the heavy liquor to drop to the bottom of the outer shell, the vapors being further expanded in the body 10 of the shell and any remaining juice or liquor accompanying the vapors will drop to the bottom of the body 10 and back to the end 11 and to outlet pipe 31, thence to be conducted back to the evaporating pans.

I would state in conclusion that while the illustrated example constitutes a practical embodiment of my invention, I do not limit myself strictly to the exact details herein il-

lustrated, since, manifestly, the same can be considerably varied without departure from the spirit of the invention as defined in the appended claims.

5 Having thus described my invention, I claim:

1. A catch-all to eliminate liquor from vapor passing to a condenser, said catch-all including an outer shell having a body of 10 truncated cone shape, said body having a vapor outlet and an oppositely disposed truncated conical end constituting a vapor inlet, said shell having an outlet for the escape of liquor, an inner pipe spaced from 15 the shell and presenting a closed end, the top portion of the pipe being perforated and the lower portion imperforate, and a baffle in front of the upper portion of said pipe, said closed end of said pipe being oblique 20 to the axis of the pipe so that the upper portion of the pipe extends beyond the lower imperforate portion, said baffle being angular in cross section and spaced from the closed end of the pipe to afford an indirect 25 passage from the inlet end of the shell to the perforations of the pipe.
2. A catch-all comprising a vapor conducting shell enlarged intermediate its inlet and outlet, a vapor discharge pipe fitted 30 into the outlet of the shell and extending toward the inlet thereof, said pipe having a perforate upper portion, and a closure for its end adjacent the inlet of the shell, said closure being disposed in a plane bringing

the upper portion of the pipe in closer relation to the inlet of the shell than the lower portion of said pipe. 35

3. A catch-all comprising a vapor conducting shell enlarged intermediate its inlet and outlet, a vapor discharge pipe fitted 40 into the outlet of the shell, and extending toward the inlet of the shell, said pipe having a perforate upper portion, and a closure for its end adjacent the inlet of the shell, said closure being disposed in a plane bringing 45 the upper and perforate portion of the pipe in closer relation to the inlet of the shell than the lower portion of the pipe, and a hood-like baffle fitted over the upper portion of the last-named end of pipe, said 50 baffle being spaced from the pipe to permit circulation of vapors therebetween.

4. A catch-all, comprising a vapor conducting shell enlarged intermediate its inlet and outlet, a vapor discharge pipe fitted 55 into the outlet end of the shell and extending toward the inlet thereof; said pipe having a perforate upper portion, and a closure for its end adjacent the inlet of the shell, said closure being disposed in a plane bringing 60 the upper and perforate portion of pipe in closer relation to the inlet of shell than the lower portion of said pipe, a hood-like baffle fitted over the upper portion of the last named end of pipe said baffle having 65 a wall disposed parallel to the end closure for pipe and spaced therefrom.

PEDRO MIR.
